UNITED STATES PATENT OFFICE.

CLARENCE M. CREWS, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed July 10, 1923. Serial No. 650,601.

To all whom it may concern:

Be it known that I, CLARENCE M. CREWS, a citizen of the United States, residing in Brooklyn Borough, in the county of Kings, 5 city and State of New York, have invented certain new and useful Improvements in Typewriting Machines, of which the following is a specification.

This invention relates to carbon-carrying 10 means in typewriting machines whereby a number of superimposed webs or continuous work-sheets may be fed through the machine, for continuous billing or other work.

15 Printed forms are usually repeated upon the plies of web, and several of these work-sheets are superimposed and fed into the machine, where they may be interleaved with carbon-sheets preparatory to typing.

20 A small amount of work would not warrant the purchase of a machine built especially for continuous billing, and therefore one object of the invention is to provide means that may be used with an ordinary 25 typewriting machine.

Another object of the invention is to provide means whereby the carbon-sheets may be transferred from a completed form to the next succeeding form to be typed by 30 means of stripping, as in the fan-fold machine, without the necessity of displacing the platen of the typewriter.

In securing these ends, a back or base, 35 preferably made of cardboard or other tough, though flexible, material, has formed therein a plurality of transverse slots, which divide a portion of the base into a plurality of transverse strips to which are fastened a plurality of carbon-sheets of any 40 desired length to suit the length of the work-sheet sections. The back of the pack is also furnished, preferably near the corners of its trailing edge, with hooking or stopping members. The leading ends of 45 the webs may be threaded through the slots, to interleave them with the carbon-sheets, and be brought forward until they register with the leading end of the flexible back. The leading end of the back thus forms a 50 gage for the work-sheets, which will bring the carbon-sheets with their leading ends in position to transfer matter that is typed upon the first writing line of the first form.

55 The combined pack thus formed is fed into the machine in the usual manner of feeding

an ordinary work-sheet, and is advanced by means of the ordinary feed-roll mechanism, until its leading edge has passed beneath a web-severing knife, and the first line of writing on the first form appears at the 60 printing point. The matter to be transcribed to the first form is now typed thereon.

At the conclusion of the typing operation, the carbon-pack and work-sheets are advanced together, either by means of rotating the platen in the usual manner or by releasing the feed-rolls, grasping the leading edge of the combined pack and advancing it with the fingers, until the retaining hooks 65 on the carbon-pack become fastened over the edge of the rear paper-table of the machine, in which position they will prevent any further forward movement of the carbon-pack itself. 70

The feed-rolls being released, the leading ends of the work-sheets alone may be grasped by the fingers, and pulled forward beyond the leading end of the back of the carbon-pack, stripping the carbons from the 75 web-plies, until the line of separation between the first and second printed forms registers with the leading edge of the back of the carbon-pack. This operation of the web, relatively to the web-rider strips the 80 carbon-sheets from the first form and places them in position with their leading ends to transfer matter typed upon the first writing line of the second form. It will be observed, in case the forms are of such a 85 length as would make it uncomfortable to withdraw them during this operation by grasping the leading ends of the work-sheets with the fingers of only one hand, that the side edges may be grasped by the 90 fingers of both hands in repeated motion, the hooking or stopping members holding the trailing end of the carbon-pack or web-rider stationary without the necessity of further holding it with one hand. There 95 being preferably a hook or stop on each side of the trailing end of the carbon-pack, they will also prevent skewing of the pack or rider when the feed-rolls are released during the stripping operation. 100

The feed-rolls may now be thrown on again, and both the web-rider or carbon-pack and the work-sheets may be back-fed together until the line of separation mentioned is opposite the cutting edge of the 105 110

knife, in which position the first form is ready to be torn off, and the second form is in position to be typed upon, with the first writing line of the latter at the printing point. After severing the first form from the work-sheets, the entire operation may be repeated.

It will be noted that typing upon one form is completed, and another form interleaved with carbons, and brought with its first writing line to the printing point, ready to be typed upon, without displacing the platen at any point in the operation, and without removing the work-sheets from the machine.

It will also be noticed that the machine in which this has been accomplished is an ordinary typewriter, to which has been added only a standard collating table which bears a web-severing knife, accessories that require only a moment, and no changing of the machine, to fasten in place.

In other words, the use of the invention with an ordinary typewriter, fitted with the accessories mentioned, enables a typist to accomplish the same work that is usually done upon a much more expensive and complicated machine, with as much ease and speed as could be had with that machine.

Other features and advantages will hereinafter appear.

In the accompanying drawings,

Figure 1 is a perspective view of the invention as it appears when bent around the platen of a typewriter, and shows the manner in which carbon-sheets are fastened to members between slots which are formed in the back of the pack to admit continuous work-sheets.

Figure 2 is a sectional view of parts of the carriage of a typewriting machine, and shows the carbon-sheets interleaved between the leading ends of the continuous work-sheets which have been fed through the machine, and typed upon, until the first printed form thereon has been completed.

Figure 3 is a sectional view, similar to Figure 2, and shows the combined pack advanced through the machine to the point where the transfer of carbon-sheets is about to take place.

Figure 4 is a sectional view, similar to Figure 3, except that it shows the leading ends of the work-sheets advanced to strip the carbons from the first form and to bring them into position for the second form.

A platen 5, rotated by the ordinary line-spacing mechanism 6 or platen-knob 7, is mounted in a carriage 8, to move transversely of the typewriter on a rail 9, supported in the frame 10 of a typewriting machine. The usual feed-rolls 11 and 12 co-operate with the platen 5 in feeding work-sheets through the machine, which is furnished with type-bars 13. The carriage 8 is provided

with a rear paper-table 14, on which are mounted two paper-guides 15 of the usual sort.

There may be mounted on top of the carriage 8, by means of brackets 16 and a cross-member 17, an ordinary collating table 18, which may be furnished with an adjustable web-severing knife 19. A carbon-pack or carrier 20 is preferably made with a stiff back-member 21, in which may be formed a plurality of transverse slots 22 separated from one another by members 23, to which may be fastened carbon-sheets 24. The back 21 is a web-rider, as it is shifted upon the web at intervals, and it is preferably furnished near the corners of its trailing end with hooking or stopping members 25.

In operation, a number of continuous work-sheets 26^a, which may have work-sheet sections indicated thereon, may be superimposed to form a pack 26. With the carbon-pack 20 laid flat, the leading edges of the continuous work-sheets 26^a are threaded, one through each slot 22, and brought forward until they register with the leading end of the web-rider or back-member 21. The leading edge of the combined pack 27, thus formed is fed into the machine in the same manner as used for an ordinary work-sheet, and is advanced, by employing the line-spacing mechanism 6 or platen-knob 7, to bring the first writing line of the first work-sheet section to the printing point. The matter to be typed upon the first work-sheet section is now transposed.

As this typing operation progresses, the leading edge of the combined pack 27 is guided beneath the web-severing knife 19, and over the collating table 18. The completion of the typing operation mentioned will bring the combined pack 27 to the position shown in Figure 2.

The combined pack 27 is now advanced, either by rotating the platen by means of the platen-knob 7, or by releasing the feed-rolls 11 and 12 and grasping the leading edge of the combined pack 27 to draw it forward with the fingers, until the hooking or stopping members 25 engage the edge of the rear paper-table 14, which will bring it to the position shown in Figure 3.

If the feed-rolls 11 and 12 were not released to accomplish the operation just finished, they must now be released so that the leading ends of the work-sheets 26^a alone may be grasped and pulled beyond the leading edge of the back 21 of the carbon-pack 20, until the line of separation between the first work-sheet section, which has just been completed, and the succeeding work-sheet section of the continuous work-sheets 26^a is opposite the leading end of the back 21. This operation strips the carbon-sheets 24 from between the continuous work-sheets 26^a at the first work-sheet section, and transfers them to their

proper position between the continuous work-sheets 26^a at the second or succeeding work-sheet section, where they will be in position to transfer matter typed upon the second work-sheet section.

The feed-rolls 11 and 12 are now thrown on again, and the platen fed in reverse line-space direction, by means of the platen-knob 7, until the line of separation between the first and second work-sheet sections is opposite the cutting edge of the knife 19. The completed leading work-sheet section now may be severed from the pack; the knife 19 having been positioned previously, so that, when the line of separation at the bottom of one work-sheet section is opposite the cutting edge, the first writing line of the next succeeding work-sheet section thereto will be at the printing point, ready to be typed upon; and the entire operation repeated.

It is understood, of course, that the members 23 may be loosed at one end to admit the plies of a fan-folded web, instead of the work-sheets 26^a, to the slots 22, in which case the operation, after threading the carbon-pack 20 with the work-sheet plies, will be exactly similar to that described above.

A paper-guide 28 may be mounted upon the type-bar segment 13^a to hold the combined pack 27 closely adjacent to the platen 5.

Variations may be reported to within the scope of the invention, and portions of the improvements may be used without others.

Having thus described my invention, I claim:

1. The combination with a typewriting machine having a rear paper-table, and a revoluble platen, of a flexible carbon-carrier having a plurality of transverse openings, and a plurality of carbon-sheets mounted upon transverse members adjacent thereto, said carrier arranged to have the plies of a plurality of continuous work-sheets threaded through said openings and interleaved with said carbon-sheets, to form a work-pack to be fed underneath and around said platen, said carbon-carrier being provided with stops to co-operate with said rear paper-table to hold said carrier from movement while said work-sheets are being drawn through said openings and beyond said carbon-sheets.

2. The combination with a typewriting machine having a revoluble platen and a rear paper-table, of a flexible carbon-carrier arranged to be threaded around the platen with the plies of continuous billing forms, the carbons being interleaved with the plies, and means carried by the trailing end of said carrier, and arranged to engage the paper-table to hold said flexible carrier while the plies are shifted in line-feeding direction relatively to the carbons to strip the latter from typed sections of the plies, the leading edge of said carrier forming a gage for co-

operating with said plies during such carbon-stripping operation.

3. A carbon-carrier for enabling a typewriting machine to manifold a multiple-ply work-web, comprising a sheet of flexible material having a series of transverse slits therein to form carbon-blades therebetween, each of said slits arranged to have a single ply of a plurality of superposed plies of work-web threaded therethrough, and brought forwardly, so as to overlie a carbon, the composite pack to be entered beneath the platen from the rear of the machine and fed upwardly thereover during typing.

4. In a typewriting machine for typing upon superposed continuous work-plies fed to the machine from the rear thereof, the combination with a revoluble platen, of a carbon-carrier comprising a sheet of flexible material having a plurality of transverse openings therein, and between which carbons are fixed and interleaved with work-plies led through said openings, said carrier being long enough to extend around the platen when the carbons have been run above and free thereof, and means for positively holding said carrier so as to maintain said carbons in such position, during shifting operations between the latter and the work-plies.

5. A web-riding carbon-carrier comprising an elongated sheet of flexible material having a series of transverse openings adjacent its mid-section and carbon-sheets attached to portions of said sheet between said openings, the plies of a multiple-ply web being threaded through said openings, the web and carrier being relatively shiftable to strip the carbons.

6. In a typewriting machine having a platen, a flexible carbon-stripper having a series of transverse slits through which work-webs are threaded, the stripper being carried by the work-webs, and carbons attached to said stripper and interleaved between the work-webs, the stripper and the webs being relatively shiftable to strip the carbons to shift them to new positions along the work-webs.

7. In a typewriting machine having a platen, a flexible carbon-stripper having a series of transverse slits through which work-webs are threaded, the stripper being carried by the work-webs, and carbons attached to said stripper and interleaved between the work-webs, the stripper and the webs being relatively shiftable to strip the carbons to shift them to new positions along the work-webs, the leading end of the stripper extending sufficiently in advance of the slits to form a backing for the carbons, said carbons extending from said slits toward said leading end.

8. In a typewriting machine having a platen, a flexible carbon-stripper having a series of transverse slits through which

work-webs are threaded, the stripper being carried by the work-webs, and carbons attached to said stripper and interleaved between the work-webs, the stripper and the webs being relatively shiftable to strip the carbons to shift them to new positions along the work-webs, the leading end of the stripper extending sufficiently in advance of the slits to form a backing for the carbons, said

carbons extending from said slits toward 10 said leading end, and the trailing end of the stripper extending down under the platen to be gripped by the feed-rolls when the slits lie above the platen; and a web-table extending up from the delivery side of the 15 platen.

CLARENCE M. CREWS.

work-webs are threaded, the stripper being carried by the work-webs, and carbons attached to said stripper and interleaved between the work-webs, the stripper and the webs being relatively shiftable to strip the carbons to shift them to new positions along the work-webs, the leading end of the stripper extending sufficiently in advance of the slits to form a backing for the carbons, said

carbons extending from said slits toward 10 said leading end, and the trailing end of the stripper extending down under the platen to be gripped by the feed-rolls when the slits lie above the platen; and a web-table extending up from the delivery side of the 15 platen.

CLARENCE M. CREWS.
